UNITED STATES PATENT OFFICE

GEORGE L. BRIDGE, OF CLAYTON, MISSOURI

DESIGN FOR A COAL STOVE

Application filed March 16, 1933. Serial No. 47,468. Term of patent 14 years.

To all whom it may concern:

Be it known that I, GEORGE L. BRIDGE, a citizen of the United States, residing at Clayton, St. Louis County, Missouri, have invented a new, original, and ornamental Design for a Coal Stove, substantially as shown in the accompanying drawing, in which—

The figure is a perspective view of a coal stove showing my new design.

I claim:

The ornamental design for a coal stove, substantially as shown.

GEORGE L. BRIDGE.
